To all whom it may concern:

Be it known that I, EDWARD BRUNHOFF, a citizen of the United States, residing at Cincinnati, in the county of Hamilton and State 5 of Ohio, have invented and produced a new and original Design for a Casing or Frame for Vending-Machines, of which the following is a specification, reference being had to the drawing, forming a part thereof, in which the 10 figure represents a perspective view of a casing or frame for vending-machines embodying my new design.
